UNITED STATES PATENT OFFICE.

GODFREY W. GOSS, OF KOKOMO, INDIANA.

CARBON TRANSMITTER.

SPECIFICATION forming part of Letters Patent No. 605,575, dated June 14, 1898.

Application filed April 20, 1897. Renewed February 7, 1898. Serial No. 669,450. (No model.)

To all whom it may concern:

Be it known that I, GODFREY W. GOSS, a citizen of the United States, residing at Kokomo, in the county of Howard and State of Indiana, have invented a new and useful Carbon Transmitter, of which the following is a specification.

This invention relates to certain improvements in carbon transmitters, and has for its object to provide a device of this character of a novel and simple nature provided with means for maintaining the carbon of the transmitter in a pulverulent or powdered condition, so as to permit the same from becoming packed or hardened, whereby the efficiency of the transmitter will be impaired.

The invention consists in a transmitter having its carbon-holder provided with an agitator device adapted to be moved therein in order to agitate or stir the pulverized carbon when the same shall have become packed or hardened from dampness or any other cause, so as to maintain the variable resistance.

The invention also contemplates certain novel features of the construction, combination, and arrangement of the various parts of the improved transmitter whereby certain important advantages are attained, and the device is made simpler, cheaper and otherwise better adapted and more convenient for use, all as will be hereinafter fully set forth.

The novel features of the invention will be carefully defined in the claims.

In order that my invention may be the better understood, I have shown in the accompanying drawings a carbon transmitter provided with my improvements, in which—

Figure 1 is a sectional view taken axially through the transmitter provided with my improvements. Fig. 2 is a sectional view taken through the carbon-holder, but showing the sleeve and binding-post thereof in elevation. Fig. 3 is a face view of the carbon-holder, showing the agitator in place therein.

In the views, 1 indicates the casing of the transmitter, and 2 indicates the diaphragm arranged in front of the carbon-holder 3, which is held in the casing in the usual way, said casing and carbon-holder being, as shown in Fig. 3, of circular form, and the carbon-holder being provided in its front face with a cham-

ber for the reception of the pulverized carbon, as shown at 4.

The carbon-holder 3 is connected with the end of a sleeve 5, one end of which communicates with the chamber 4, wherein is held the powdered carbon, while the opposite end of said sleeve extends from the rear surface of the carbon-holder outside of the casing 1 and is provided with a screw-threaded portion 6, whereon is held a nut 7 for securing the carbon in place in the casing, said screw-threaded portion being also provided with a nut 8, serving to hold to said sleeve a wire or conductor, the sleeve forming a binding-post 60 by means of which such conductor may be electrically connected with the carbon-holder 3.

In the bore or axial hollow of the sleeve 5 is arranged a spindle 9, rotative therein and having one end extended into the chamber 70 wherein is held the pulverized carbon 4, the opposite end of said spindle or stem 9 being arranged to project beyond the rear end of the sleeve 5, as clearly shown in Fig. 1, and being provided at its projecting rear end with 75 a head or enlargement 10, forming a knob or handle by means of which the spindle may be turned or operated within the sleeve.

The forward end of the spindle or stem 9, or that end thereof which projects into the 80 chamber in the front face of the carbon-holder, is provided with oppositely-projecting arms 11, held in place to the spindle or stem by means of a screw 12, said arms 11 being, as shown in Fig. 1, curved to conform to the walls 85 of the chamber wherein the powdered carbon is contained and forming an agitator by means of which the powdered carbon in said chamber may be stirred or agitated.

By this construction and arrangement of 90 the parts it will be seen that when the powdered carbon 4 contained in the chamber of the front face of the carbon-holder 3 shall have become packed or hardened from any cause whatever the spindle or stem 9 may be 95 turned or rotated within the sleeve 5, so that the arms 11 on the end of said stem or spindle will stir up or agitate the powdered carbon 4 and prevent the efficiency of the transmitter from becoming impaired.

It will also be seen from the above description that the device constructed in accordance

with my invention is of an extremely simple and inexpensive nature and is especially well adapted for use in connection with carbon transmitters, since it permits of conveniently 5 stirring or agitating the powdered carbon from time to time, as may be necessary, and it will also be obvious from the above description that the invention is capable of some modification without material departure from 10 its principles and spirit, and for this reason I do not wish to be understood as limiting myself to the precise form and arrangement of the parts herein set forth.

Having thus described my invention, I 15 claim—

1. In a carbon transmitter, the combination of a carbon-holder having a chamber to receive the powdered carbon, and an agitating device separate from the carbon-holder and 20 arranged within the chamber thereof for agitating the powdered carbon in said chamber, independently of any movement of said carbon-holder, substantially as set forth.

2. In a carbon transmitter, the combination 25 of a carbon-holder having a chamber to receive the powdered carbon, and a stirring device disassociated from said carbon-holder and arranged in said chamber to agitate the carbon therein without affecting the adjustment of the carbon-holder, substantially as set forth.

3. In a carbon transmitter, the combination 30 of a carbon-holder having a chamber for the reception of powdered carbon, and a rotative stirring device disassociated from said carbon-holder and arranged in said chamber to agitate the powdered carbon therein without affecting the adjustment of said carbon-holder, substantially as set forth.

4. In a carbon transmitter, the combination 35 of a carbon-holder having a chamber to receive the powdered carbon, a movable stem or spindle, and a stirring device carried on said stem or spindle and extending in said chamber, said stirring device being independent of the carbon-holder and arranged when the stem or spindle is moved to agitate the powdered carbon in the chamber without affecting the adjustment of said carbon-holder, 40 substantially as set forth.

5. In a carbon transmitter, the combination 45 of a carbon-holder having a chamber for the reception of powdered carbon, a rotatively-mounted stem or spindle, and a stirring device carried by the stem or spindle and ar-

ranged in the chamber, said stirring device being independent of the carbon-holder and adapted when the stem or spindle is turned to agitate the powdered carbon in said chamber without affecting the adjustment of said 60 carbon-holder, substantially as set forth.

6. In a carbon transmitter, the combination of a carbon-holder having a chamber for the reception of powdered carbon, a sleeve carried by the carbon-holder and having one end 65 adapted for communication with the chamber thereof, a stem or spindle movable in said sleeve, and a stirring device carried by the stem or spindle and extending in said chamber, said stirring device being arranged when 70 the stem or spindle is moved to agitate the powdered carbon in said chamber, substantially as set forth.

7. In a carbon transmitter, the combination of a carbon-holder having a chamber for the reception of powdered carbon, a sleeve connected electrically with the carbon-holder and having one end adapted for communication with the chamber thereof and its opposite end provided with a binding-post, a stem or spindle movable in the sleeve, and a stirring device carried on said stem or spindle and extending in said chamber, said stirring device being adapted when the stem or spindle is moved to agitate the powdered carbon in said 85 chamber, substantially as set forth.

8. In a carbon transmitter, the combination of a carbon-holder having a chamber for the reception of powdered carbon, a sleeve connected with the carbon-holder and having one 90 end adapted for communication with the chamber thereof, a stem or spindle arranged to turn in said sleeve and having one end projecting beyond the rear end of the sleeve and provided with an enlargement by means 95 of which it may be turned, and a stirring device carried on the opposite end of the stem or spindle and extending into the chamber in the carbon-holder, said stirring device being arranged, when the spindle or stem is turned, 100 to agitate the carbon contained in said chamber, substantially as set forth.

In testimony that I claim the foregoing as my own I have hereto affixed my signature in the presence of two witnesses.

GODFREY W. GOSS.
